UNITED STATES PATENT OFFICE.

PIOTR JASINSKI AND JAN SMOGALA, OF WELLAND, ONTARIO, CANADA.

ANTISUBMARINE DEVICE.

1,322,576.

Specification of Letters Patent. Patented Nov. 25, 1919.

Application filed July 19, 1918. Serial No. 245,617.

To all whom it may concern:

Be it known that I, PIOTR JASINSKI, a subject of the King of England, residing at Welland, Prov. of Ontario and Dominion 5 of Canada, and I, JAN SMOGALA, a subject of the King of England, residing at Welland, Prov. of Ontario and Dominion of Canada, have invented certain new and useful Improvements in Antisubmarine Devices, of which the following is a specification.

This invention relates to improvements in antisubmarine devices, and particularly to types in which a net may be held extended 15 at some distance from the hull of the ship so as to completely encircle the same below the water line.

The principal object of the invention is to provide means whereby the extending nets 20 may be quickly and rigidly secured or released from their supports by mechanism operated from the deck of the ship.

These and other like objects are attained by the novel construction and combination 25 of parts hereinafter described and shown in the accompanying drawing, forming a material part of this disclosure, and in which:—

Figure 1 is a side elevational view, showing 30 a conventional type of ship, together with the surrounding net held by supports made in accordance with the invention.

Fig. 2 is an enlarged fragmentary transverse sectional view, taken through a portion 35 of the hull of the ship, showing the net and its supporting means.

Fig. 3 is a top plan view of the same, and

Fig. 4 is a perspective view, showing the bracket supports, by which the nets are suspended.

Engaged with the hull 10 of the vessel are a plurality of equally spaced bracket supports 14 in which are fixed diverging bars 15, other lower brackets 18 being also secured 45 to the hull of the vessel from which extend upwardly and outwardly bars 19, their outer ends being engaged in suitable openings formed in elements 20 in which are also rigidly secured the outer diverging ends of the 50 bars 15.

Formed in the elements 20 are outwardly extending rigid jaws 22, containing semi-circular recesses 23, adapted to receive a rail 24, from which the net 25 is suspended.

55 In order to hold the rails 24 rigidly en-

gaged within the elements 20, caps 26 are provided, the same having recesses opposed to the recesses 23, and extending shanks 27, which are engaged upon spindles 28, pivoted in the upper portion of the brackets 20. 60

Affixed upon the center of the spindles 28 is a lever 30 extending upward, and joined to it a link 31, extending toward the hull of the ship, parallel with the plane of the support bars 15, and is connected at its inner 65 end with one arm 33 of a bell-crank lever, pivoted in clip brackets 34 secured upon the angularly disposed support bars 15.

The outer arm 35 of the bell-crank lever has engaged with it a link 36, engaging the 70 outstanding arm 38 of another bell-crank lever, pivoted upon brackets 39, secured to the upper portion of the hull of the ship, the outer arm 40 of the bell-crank lever being pivoted to the end 41 of a screw 42 operable 75 within fixed brackets 43 secured upon the deck of the ship.

This screw is provided with an operating crank handle 44, by which it may be manually turned. Thus, when it is desired to release the rails 24, which support the net 25, the crank handle 44 is actuated so as to operate the several bell-crank levers, raising the leaf or cap elements 26, so that the rails 24 can be readily removed. 85

From the foregoing it will be seen that an effective device has been disclosed in which the supporting rails may be engaged at any time, and when the caps 26 have been raised, it is possible to remove the rails 24, together 90 with the nets.

Having thus described our invention what we claim as new, and desire to secure by Letters Patent, is:—

In a device of the character described, in 95 combination, a plurality of upper and lower bracket supports secured to the outer hull of a ship, an outwardly extending bar secured in each of said brackets, elements secured to the outer ends of each pair of bars 100 extending from an upper and a lower bracket respectively, outwardly extending rigid jaws formed in said elements having semi-cylindrical recesses adapted to receive a rail, caps journaled in said elements, cooperative with said jaws to secure said rail in position, a lever formed with spindles upon which the shanks of said caps are engaged, a bell-crank lever mounted in clips 105 on the bars extending from the upper brack-

ets, connections between said bell-crank lever and the lever of said caps, a bell-crank lever connected to a bracket secured to the upper part of the hull, a link connecting one arm of the first named bell-crank lever to one arm of the last named bell-crank lever, a bracket secured on the deck of the ship, and a screw operatively

engaged in said bracket supporting said screw, said screw actuating the last named bell-crank lever.

In testimony whereof we have affixed our signatures.

PIOTR JASINSKI.
JAN SMOGALA.
